TOY MORTAR

Saul Robbins, 35 Mountain Way, West Orange, N.J., and Isaac Heller, 2080 Arrowwood Drive, Scotch Plains, N.J.

Filed Sept. 2, 1960, Ser. No. 61,994

Term of patent 14 years

(Cl. D34—15)

FIG. 4

Fig. 2Fig. 3Figure 1 is a side elevation of a toy mortar showing our new design, the other side being a mirror image thereof;

We claim:

The ornamental design for a toy mortar, as shown and described.
